REEL

Donald C. Hardie, Easton, Pa., assignor to Chipman Spinning Mills, Inc., Easton, Pa., a corporation of Pennsylvania

Application July 20, 1944, Serial No. 545,802

7 Claims. (Cl. 242—110)

This invention relates to reels, and has reference more especially to reels useful in the textile industry to revolvably support yarn supply packages or skeins, for example, annular "cakes" of rayon as they come from the manufacturer, incident to spinning and spooling operations or other subsequent processing.

In connection with reels of the kind referred to, I aim to provide for the firm support and positive retainment of the yarn packages throughout the period of unwinding, and yet permit quick and easy application of the packages without necessitating disassembling of any of the parts of the reels or the use of any tools for the purpose.

One way in which the foregoing and other objects and attendant advantages may be attained in practice with economic use of readily available materials and at relatively small cost of manufacture will appear from the following detailed description of the attached drawings, wherein

Fig. 1 is a fragmentary view in top plan of a portion of a creel frame with a reel conveniently embodying my invention, journalled for free rotation thereon.

Fig. 2 is a view showing the reel in end elevation.

Fig. 3 is an axial section of the reel.

Fig. 4 is a view similar to Fig. 3 but showing the reel prepared for application of a yarn package.

Fig. 5 is a perspective view of the hub member of the reel;

Fig. 6 is a detail sectional view taken as indicated by the angled arrows VI—VI in Fig. 3; and

Fig. 7 is a view corresponding to Fig. 1, of a modified reel constructed and arranged in accordance with my invention for non-rotative support and over end delivery of the yarn from the yarn package.

With reference first more particularly to Figs. 1-4 of these illustrations it will be noted that my improved reel, in the form there shown, has a core or hub member 10, and a skeleton body or drum 11. The hub member 10 may be of wood and in the present instance is provided at opposite ends with gudgeons or trunnions 12 adapted to be received in the open bearings of the creel frame 13 as shown in Fig. 1. In accordance with my invention, the skeleton drum of the reel is constituted by a plurality of radially-arranged counterpart components which are fixedly attached to the hub member in a manner presently explained. Each component 15 of the skeleton drum 11 is fashioned from a single length of spring wire so bent as to provide a relatively sharp angled horizontally elongate U-shaped yarn package engaging portion 16 which normally extends substantially parallel to the reel axis as

in Fig. 3, and a similarly disposed sustaining spring portion 17 of hair spring configuration, whereof the legs are outwardly bowed in relation to each other, also as clearly shown in Fig.

5 3. In each of the elements 15, one end of the wire is finished off with a closed eye as at 18 at one side of the U-shaped portion 16, while the latter at its other side merges with one leg of the sustaining spring portion 17 through a flat 10 outstanding retroversion or loop 19. The other or anchorage leg of the spring portion 17 of each element 15 connects through a multi-turn spiral 15 20 with the first mentioned leg of said spring portion, and is flattened somewhat as at 21 and has its end bent at right angles to provide an anchorage lug 22.

In assembling the reel parts, the anchorage lugs 22 of the skeleton drum components 15 are 20 individually inserted into radial socket holes 23 provided for their reception around the hub member 10 adjacent one end thereof as shown in Fig. 3, and the flattened segments 21 of the anchorage legs of the spring portions 17 lodged in longitudinal recessions or flutings 25 likewise 25 provided on said hub member and aligned with said holes as shown in Figs. 3 and 5. Finally a tight fitting slip ring 26 is forced over the hub member 10 so as to embrace the anchorage legs of the spring portions 17 of the components 15 30 at the region of their embedment and so rigidly hold said components definitely positioned relative to said hub member.

In preparation for the application of a yarn package P, the skeleton drum 11 is inwardly compressed, that is to say, the package-engaging portion 16 of each of its components 15 is depressed toward the hub member 10 and locked laterally beneath the coil 20 of the hair spring sustaining portion 17 as shown in Fig. 4. With this accomplished, the collapsed drum 11 is thrust, contracted end forward, into the hollow of the annular yarn package, whereupon the portions 16 of the components 15 are released into engagement with the inner periphery of the yarn package. 40 The springs 17 are so designed as to constantly exert gentle pressure upon the yarn package from within until the yarn is completely run off, and will moreover adapt themselves to internal irregularities or variations in the internal diameters of different packages. The package is thus firmly supported with the reel running freely in the bearings 13 (Fig. 1), its retainment being assured by the end guards jointly formed on the skeleton drum 11 by the sides 18 and 19 of the U-shaped portions 16 of the several components 15.

In Fig. 7 the reel of my invention, slightly modified for use in the over end delivery of the yarn Y from the package P, is illustrated. For the support of the reel I have shown a bar or

rail 27 which is provided with an aperture 28 for the snug reception of one of the gudgeons 12, i. e., the gudgeon adjacent the region of anchorage of the radial components 15 in the hub 10. The modified reel is identical with the first described one except in that the free ends of the yarn package engaging portions 16 of its radial components 15, which portions are in the form of cantilever extensions of the spring portions 17, are bent outwardly at an angle of about twenty-five or thirty degrees as at 18a instead of at right angles. In order to keep the yarn Y running outward during over end delivery, I have provided, for association in concentric relation with the reel, a yarn deflecting disk 29 which may be of fiber or the like with a smooth rounded edge and of a diameter somewhat larger than that of the reel body whereby the yarn Y is deflected as shown to clear the guard projections 18a until the last round is removed. As shown, the deflecting disk 29 is centrally apertured as at 30 to fit snugly over the uppermost gudgeon 12. In all other respects the modified reel of Fig. 7 is identical with that featured in Figs. 1-4, and accordingly, in order to preclude repetitive description, all corresponding parts in the modification have been identified with the same numerals previously employed.

While I have described my improved reels in forms suited to the textile industry, they can obviously be adapted, through modifications within the scope of the appended claims, for use in other arts.

Having thus described my invention, I claim:

1. A reel comprising a hub member with a series of radial socket holes and longitudinally-extending flutings aligned with said holes; a skeleton body formed by a plurality of radially-arranged components each fashioned from wire or the like with a yarn package engaging portion substantially in parallel relation to the reel axis and a sustaining leg portion, the free end of said leg portion being recessed into one of the flutings of the hub member and having a laterally directed terminal projection engaged in the corresponding socket hole; and a retaining collar on the hub member tightly-fitting over the embedded leg ends of the reel body components.

2. A reel comprising a hub member; a compressible skeleton drum body capable of supporting and retaining an annular yarn package or skein, said body being formed by a plurality of radially-arranged independently-yieldable components each fashioned from wire with a yarn package engaging portion in parallel relation with the reel axis and with a similarly arranged sustaining spring portion whereof one end is secured to the hub member; and means on said spring portions releasably engageable by the yarn package engaging portions upon depression of said components to hold the reel collapsed.

3. A reel comprising a hub member with a series of radial socket holes and longitudinally-extending flutings in registry with said holes; a compressible skeleton drum body for supporting and retaining an annular yarn package or skein, said body being formed by a plurality of radially-arranged independently-yieldable components each fashioned from wire or the like with a U-shaped yarn package engaging portion in parallel relation to the reel axis and with a similarly arranged sustaining spring portion of hair pin configuration whereof one leg is connected to one

corner of the U-shaped portion, the free end of the other leg being recessed into one of the flutings of the hub and having a lateral terminal projection engaged in the corresponding socket hole; and a retaining collar on the hub member forced over the embedded ends of the reel body components.

4. A reel comprising a hub member with a series of radial socket holes and longitudinally-arranged flutings in registry with said holes; and a compressible skeleton drum body for supporting and retaining an annular yarn package or skein, said body being formed by a plurality of radially-arranged independently-yieldable components each fashioned from wire or the like with a U-shaped yarn package engaging portion in parallel relation to the reel axis and with a similarly arranged sustaining spring portion of hair pin configuration whereof one leg is connected to one corner of the U-shaped portion and whereof the other leg is secured to the hub member, said legs being united through a multi-turn spiral beneath which the package-engaging portion is releasably locked upon depression toward the reel axis in preparation of the reel for reception of the yarn package.

5. A reel for over-end yarn delivery comprising a hub member; and a skeleton drum body for supporting an annular yarn package consisting of a plurality of components which radiate from the hub member, each such component being fashioned from a single length of wire or the like with a sustaining arm portion connected to the hub member, a yarn package engaging portion parallel to the reel axis in the form of a cantilever extension of the arm portion, and a guard projection formed by an outward retroversion of the wire at the juncture of said yarn package engaging portion with said arm portion.

6. A reel intended for over end yarn delivery, comprising a hub member; a skeleton drum body for supporting an annular yarn package consisting of a plurality of components which radiate from the hub member, each such component being fashioned from wire or the like with a yarn package engaging portion parallel to the reel axis whereof one end is free and the other end provided with an outward guard projection, and with a sustaining leg portion extending from the latter end of the package engaging portion to the hub member; and a yarn deflecting disk of a diameter somewhat larger than that of the reel body removably connected to the hub member and abutting the free ends of the yarn package engaging portions of the body components.

7. A reel for over end yarn delivery comprising a hub member with a gudgeon at one end; a skeleton drum body for supporting an annular yarn package consisting of a plurality of components which radiate from the hub member, each such component being fashioned from wire or the like with a yarn package engaging portion parallel to the reel axis whereof one end is free and the other end provided with an outward guard projection, and with a sustaining leg portion extending from the latter end of the yarn package engaging portion to the hub member; and a centrally apertured yarn deflecting disk of a diameter somewhat larger than that of the reel body, removably engageable over the gudgeon aforesaid to abut the free ends of the yarn package engaging portions of the body components.

DONALD C. HARDIE.
